US00D991893S

(12) **United States Design Patent** (10) **Patent No.:** **US D991,893 S**
(45) **Date of Patent:** **** Jul. 11, 2023**

(54) **SERVER FAN MODULE**

(71) Applicant: **Intel Corporation**, Santa Clara, CA (US)

(72) Inventors: **Aleksander Magi**, Portland, OR (US); **Duck Young Kong**, Beaverton, OR (US); **Daniel Surratt**, Cornelius, OR (US); **Michael Hyde**, San Francisco, CA (US)

(73) Assignee: **Intel Corporation**, Santa Clara, CA (US)

(**) Term: **15 Years**

(21) Appl. No.: **29/756,148**

(22) Filed: **Oct. 26, 2020**

Related U.S. Application Data

(62) Division of application No. 29/695,960, filed on Jun. 24, 2019, now Pat. No. Des. 904,321.

(57) **CLAIM**

The ornamental design for a server fan module, as shown and described.

DESCRIPTION

FIG. 1 is a front, left perspective view of a server fan module.

FIG. 2 is a front view thereof.

FIG. 3 is a rear view thereof.

FIG. 4 is a left side view thereof.

FIG. 5 is right side view thereof.

FIG. 6 is a top view thereof; and,

FIG. 7 is a bottom view thereof.

The features shown in broken lines form no part of the claimed design.

1 Claim, 7 Drawing Sheets
